WHEEL

Charles W. Sinclair, Detroit, Mich., assignor to
Kelsey-Hayes Wheel Company, Detroit, Mich.,
a corporation of Delaware

Application September 27, 1948, Serial No. 148,781

Term of patent 14 years

(Cl. D14—30)

To all whom it may concern:

Be it known that I, Charles W. Sinclair, a citizen of the United States of America, residing at Detroit, in the county of Wayne and State of Michigan, have invented a certain new, original, and ornamental Design for Wheel, of which the following is a specification, reference being had therein to the accompanying drawings, forming a part thereof, wherein:

Figure 1 is a front elevation of the wheel, embodying my design;

Figure 2 is a diametric section therethrough; and

Figure 3 is a fragmentary perspective sectional view thereof.

The present design comprises as the principal and dominating features thereof that portion of the wheel body shown in full lines.

I claim:

The ornamental design for a wheel, substantially as shown and described.

CHARLES W. SINCLAIR.
